Primary Examiner — Katrina A Betton*(74) Attorney, Agent, or Firm* — Paul R. Martin(57) **CLAIM**

The ornamental design for a dip stick, as shown and described.

DESCRIPTIONFIG. 1 is a perspective view of our new design for a dip stick.
FIG. 2 is a top plan view thereof.

The bottom plan view would be a mirror image thereof.

FIG. 3 is a side elevational view of our new design for a dip stick shown in FIG. 1.
The opposite side elevational view would be a mirror image thereof.FIG. 4 is an end view from the rear or handle end of our new design; and,
FIG. 5. is an end view from the forward end of our new design.
The breaks in the drawing figures show no specific length.**1 Claim, 2 Drawing Sheets**
